A diagram of a 16-pin integrated circuit package. The pins are numbered 1 through 16, with 1 at the top left and 16 at the bottom right. The pins are arranged in two rows of eight, with the top row being longer than the bottom row.

UNITED STATES PATENT OFFICE.

CHARLES H. LANDENBERGER, OF PHILADELPHIA, PENNSYLVANIA, ASSIGNOR TO
MARY K. LANDENBERGER, OF PHILADELPHIA, PENNSYLVANIA.

JACQUARD-CARD-PUNCHING MACHINE.

1,185,335.

Specification of Letters Patent. Patented May 30, 1916.

Application filed July 16, 1913. Serial No. 779,259.

To all whom it may concern:

Be it known that I, CHARLES H. LANDENBERGER, a citizen of the United States, residing in Philadelphia, Pennsylvania, have 5 invented certain Improvements in Jacquard-Card-Punching Machines, of which the following is a specification.

The object of my invention is to provide a machine for punching cards for a jac- 10 quard machine intended to be used in a loom for weaving fabrics of the oriental rug type, in which short pieces of yarn are knotted onto the warp threads of the fabric so that the upstanding ends of the knots 15 constitute the pile of the fabric. Usually such fabrics are produced by knotting the tufts onto the warp threads by hand and they are consequently very expensive. For this reason numerous attempts have been 20 made to produce a power loom on which such fabrics can be woven. One instance of such power loom is to be found in my U. S. Patent No. 706,072, dated August 5, 1902. In such looms mechanical devices are em- 25 ployed for engaging the pieces of yarn which are to form the tufts and knotting the same around corresponding threads of the warp and in order to cover the relatively wide range of colors employed in the 30 patterns of such fabrics there must be em- ployed, in connection with each of the knotting devices of the loom, a yarn supplying device (hereinafter for convenience denomi- 35 nated a color box) supplied with yarns of as many colors as there are in the color scheme of the pattern, and each of these color boxes must be adjusted so as to present any desired one of the yarns carried thereby, to the corresponding knot forming 40 devices of the loom. Although I have de- scribed herein means for mounting such color boxes and operating them by means of an ordinary jacquard machine so as to effect the presentation of yarns of the 45 proper colors to the knot forming devices at the proper times, such means are not in- tended to be claimed herein but will form the subject of a separate application. In connection with the jacquard machine spe- 50 cially punched cards are required and my present invention relates to the machine for punching such cards.

In the accompanying drawings—Figure 1 is a plan or top view of the machine; Fig. 55 2 is a longitudinal section of the same on

the line *a*—*a*, Fig. 1; Fig. 3 is a transverse section on the line *b*—*b*, Fig. 1; Figs. 3^a and 3^b are sectional views, on a larger scale, and in different positions, of certain parts of the machine; Fig. 4 is a view showing dif- 60 ferent kinds of jacks employed in said machine for controlling the operation of the punch-locking bolts; Fig. 5 is a view showing different kinds of key-jacks employed in the machine; Fig. 6 is a diagram repre- 65 senting cards punched for effecting four successive operations of four color boxes, each presenting at each operation a color different from that of the others, and from that presented by it at each of the other 70 operations; Fig. 7 is a view, partly in side elevation and partly in section, illustrating a color box, a set of harness cords corre- 75 sponding therewith, and intervening mech- anism whereby the lifting of different har- ness cords, or of different combinations of the same, is caused to effect the desired ad- justments of the color box; Figs. 8, 9, 10 80 and 11 are diagrams each showing four groups of warp threads corresponding to four color boxes of the loom and illustrating respectively the threads of each group which are supplied with yarn, at each of four successive operations of the loom, and Figs. 12 and 13 are views illustrating cer- 85 tain modifications of my invention.

In order that the purpose of my improved card punching machine may be better understood it will probably be best to preface the description of the construction and op- 90 eration of said machine with a description of the operation of so much of the loom as will convey an understanding of the ar- rangement of the color boxes in respect to the warp threads of the loom and of the 95 means for adjusting said color boxes so as to present any desired one of the colored yarns carried thereby for the action of the corresponding knot forming device.

The warp threads of the loom are divided 100 into sets, such for instance as illustrated at *x* in Figs. 8 to 11, and for each set is pro- vided a separate color box *y*. If, for in- 105 stance, there are in a single line extending across the fabric 960 colored knots or tufts and the warp is composed of 960 pairs of threads, one pair for each knot, and is fur- thermore divided into 240 sets *x* each com- 110 prising four pairs of warp threads *w'*, *w²*, *w³* and *w⁴*, there will be 240 different color

boxes y each supplying the knot forming yarns to its own set x of warp threads, and supplying the yarn successively to each pair of warp threads of the set. In forming a 5 complete line of knots across the fabric, therefore, four successive operations of the loom will be required. During the first operation the yarns supplied by each of the 10 240 different color boxes will be applied to the first pair of warp threads w^1 of the corresponding set as in Fig. 8, not, however, by direct delivery of the yarn from the color box to the warps but by intervening delivery mechanism represented conventionally in Figs. 8 to 11 by a line z and shifting from one pair of warp threads of each set to the next on each operation of the loom. During the next operation the 15 yarns will be applied to the second pair of warp threads w^2 of each set, as in Fig. 9; during the third operation the yarns will be applied to the third pair of warp threads w^3 of each set, as in Fig. 10, and during the 20 fourth operation the yarns will be applied to the last pair of warp threads w^4 of each set, as in Fig. 11. A knot having now been formed upon each pair of warp threads from side to side of the fabric the warp threads will be shedded for the reception of 25 the binding weft thread or threads and the formation of a succeeding row of knots will then be proceeded with in like manner.

The different colored yarns are disposed in a row in each color box y and each color 30 box is adjustable longitudinally so that any desired yarn of the latter may be presented at a fixed delivery point so as to be grasped by a pair of nippers whereby a sufficient length of yarn is withdrawn from the color 35 box to form the desired knot, is then cut off and is conveyed by the nippers to the knot forming devices. Means for effecting such longitudinal adjustment of the color 40 boxes so as to present any one of the row 45 of differently colored yarns carried thereby to the nippers is represented in Fig. 7 and may be briefly described as follows: The color box y is mounted at the lower end of a parallel motion device comprising a lever 50 arm c and a link d pivotally mounted upon transverse rods c' and d' , the lever also having an arm c^2 pivotally connected at its upper end to a bar e to which reciprocating movement can be imparted at the proper 55 intervals, positive movement of the bar in one direction being due to contact of a finger e' on said bar with a swinging bar f and yielding movement of the bar in the opposite direction being effected by means 60 of a coiled spring f' connected to the finger e' . Between a bracket g depending from any suitable fixed portion of the loom and a shoulder g' on the bar e are interposed a 65 series of wedges h' , h^2 , h^4 and h^8 , these wedges having different angles of inclina-

tion, for instance the wedge h' may represent one unit of inclination; the wedge h^2 two units; the wedge h^4 four units, and the wedge h^8 eight units. This combination of wedges provides for sixteen different adjustments of the color box and hence for the employment of sixteen different colored yarns in said color box and the presentation of any desired one of said yarns to the knot forming devices of the loom.

When the bar e is moved to one extreme of its reciprocation, as in Fig. 7, the color box y is also adjusted to one extreme of its movement and the colored yarn 16 will, if the color box is retained in that position, be 70 presented to the nippers for supplying the knot forming devices. Between the stems of the wedges h' , h^2 , h^4 and h^8 are interposed studs i free to slide in a slot z' in the bar e and each of a diameter equal to the 75 distance between the stem of one wedge and that of the next when said wedges are in contact, or between the wedges themselves when they are separated as in Fig. 7. The distance between the bracket g and the shoulder g' of the bar e when said bar is 80 fully projected is such that when each of the wedges is lifted, so as to occupy said space, the latter will be filled and no retraction of the bar e by the spring f' will be permitted on the retraction of the swinging bar f , consequently the combined action of the four wedges, representing fifteen units, or the difference between the location of 85 yarn 1 and yarn 16 in the color box, will result in the presentation of yarn 16 at the delivery point. The raising of a wedge or wedges representing any less number of units will result in the presentation at the 90 delivery point of a yarn so many units removed from yarn 1, the latter being presented when none of the wedges are raised.

Each of the wedges is connected to a depending harness cord m of the jacquard machine and the yarn presented by each color 95 box on each operation of the loom will therefore depend upon the number and location or grouping of the harness cords corresponding to said color box which are raised at such operation of the loom.

Each of the harness cords m is controlled by a needle of the jacquard machine, hence each color box must be represented on each 100 card of said machine by four spaces. If all of these spaces are punched all four of the 105 needles corresponding thereto will remain in the retracted position and all four of the harness cords represented by said needles will be raised. If the space corresponding to any one of the needles is blank, however, 110 that needle will be projected by the card and harness cord corresponding to it will not be raised.

In Fig. 6 is shown a diagram of the sixteen colors of the color box, running from 1 115

- to 16, and of the manner in which a card must be punched to call either of these colors. In order to call color 1, which necessitates the remaining down of all four of 5 the wedges, all of the spaces on the card are blank, as shown in group n' card S' ; in order to call color 2, a space on the card corresponding to wedge h' is punched, as shown in group n' , card S^2 ; in order to call 10 color 3, a space on the card corresponding to wedge h^2 is punched, as shown in group n' , card S^3 ; to call color 4, spaces on the card corresponding to wedges h' and h^2 are punched, as shown in group n' , card S^4 , and 15 in like manner throughout all of the other colors until finally to call color 16, all four spaces are punched as shown in group n^4 , card S^4 , so that all of the wedges will be raised.
- 20 Each card provides for a transverse row of sixteen spaces and, as each color box requires four spaces, each transverse row of spaces on the card corresponds to four color boxes and in a loom having 240 different 25 color boxes there would have to be sixty of said transverse rows in the length of the card, the first row representing the first four color boxes, the second row the next four, and so on. As it takes four successive 30 operations of the loom to produce one complete line of knots across the fabric the cards are likewise in sets of four, one for each operation of the loom, thus considering only the first row of each of the cards S' , S^2 , 35 S^3 and S^4 card S' represents the adjustment of the first four color boxes, in order to supply yarn to the first pair of warp threads of each of the four sets α , as in Fig. 8, card S^2 represents the adjustment of said 40 first four color boxes to supply yarn to the second pair of warp threads of each set, as in Fig. 9, card S^3 governs the feeding of yarn to the third pair, as in Fig. 10, and card S^4 to the fourth pair, as in Fig. 11.
- 45 Of course, in practice, each group of spaces on each card will be punched to accord with the color which it is to call. The cards shown in Fig. 6 are punched to call the sixteen colors in regular sequence, card 50 S' calling color 1, box 1; color 5, box 2; color 9, box 3, and color 13, box 4; card S^2 calling color 2, box 1; color 6, box 2; color 10, box 3, and color 14, box 4; card S^3 calling color 3, box 1; color 7, box 2; color 11, 55 box 3, and color 15, box 4; and card S^4 calling color 4, box 1; color 8, box 2; color 12, box 3, and color 16, box 4.
- The machine which constitutes the subject of my present invention has been 60 devised with the view of punching at one and the same time a complete row on each of the four cards of a set. The construction and operation of the machine will be understood upon reference to Figs. 1 to 5 inclusive of the drawings.
- The stationary bed of the machine is composed of upper and lower members 17 and 17^a between which are formed four slots 18 for the reception of the four cards of the set, said top and bottom members also having 70 formed in them registering openings 19 each intended for the reception and guidance of a punch 20 of which there are four sets of sixteen each, one set for each card. These punches are carried by a vertically 75 movable punching head 21, as shown in Fig. 3. On the underside of the bottom member 17^a of the fixed frame are formed guideways 22 for the reception of a laterally movable carriage 23 which has step 80 by step forward movements imparted to it in any appropriate manner. In the present instance I have adopted for this purpose mechanism similar to that which controls the operation of the carriage of an ordinary type writing machine but this is simply selected as a convenient means for the purpose and is not essential.
- 85 Mounted in bearings on the carriage 23 are four rock shafts 24, 25, 26 and 27, and secured to each end of each of these rock shafts by means of depending arms 28 is a blade 24^a, 25^a, 26^a, or 27^a, which can therefore swing within a limited range from front to rear, coiled springs 29 at each end 90 of the carriage 23 serving to act upon the arms 28 so as to tend to constantly maintain the blades in the retracted position shown in Fig. 3. Guided in suitable bearings 30 mounted upon the upper member 17 100 of the fixed frame of the machine are four sets s' , s^2 , s^3 and s^4 of jacks which, for identification I will hereinafter refer to as "punch jacks", one set for each of the four cards to be punched, each of these sets comprising sixteen jacks and each set being divided into four groups, each comprising 105 four jacks 31^a, 31^b, 31^c and 31^d.
- 110 Each of the punch jacks of each group has on its under side a depending lug 32 and each of the blades 24^a, 25^a, 26^a and 27^a has on its upper face four upstanding lugs 33 one for each of the sets s' , s^2 , s^3 and s^4 of punch jacks. The lugs 33 of the blade 27^a act upon the punch jacks 31^a of each group, those of the blade 26^a upon the jacks 31^b, those of the blade 25^a upon the punch jacks 31^c, and those of the blade 24^a upon the punch jacks 31^d. The lugs 33, however, 115 are so disposed as to act upon the punch jacks of only one group at a time, for instance, as shown in Fig. 1, the lugs 33 are disposed so as to act upon the punch jacks of the first group of set s' , the lugs corresponding to set s^2 being one step of the carriage 23 behind the punch jacks of the first group of set s^2 and the lugs corresponding to sets s^3 and s^4 being, respectively, two steps and three steps behind the punch jacks of the first groups of those sets. The 120 125 130

swinging blades will therefore operate upon the punch jacks of the first group of each set in succession, then upon those of the second group, then upon those of the third group, and then upon those of the fourth group.

Each of the punch jacks of each of the sets s' , s^2 , s^3 and s^4 acts upon the head of a bolt 34 guided in the punch carrying head 21 and normally retained in the retracted position shown in Figs. 3 and 3^b by means of a spring 35 surrounding the contracted stem of said bolt and acting upon the head of the same. When thus retracted the bolt 34 offers no resistance to the rise of its corresponding punch 20, when, on the descent of the head 21, the lower end of said punch contacts with a card. When either of the punch jacks 31^a, 31^b, 31^c or 31^d is projected, however, it will project its corresponding bolt 34 and the latter will be held in the projected position by means of a spring-actuated trigger 36 which drops behind the rear end of the bolt, as shown in Fig. 3^a, each projected bolt serving to lock its corresponding punch so that on the descent of the head 21 each one of the punches so locked will form an opening in the card upon which it acts. As the punching head 21 approaches the limit of its downward movement the tails of the triggers 36 strike and deflect, as shown in Fig. 3^a, a bar 37, suspended from a pivotally mounted rod 38 so that it is capable of swinging rearwardly from the position shown in Figs. 3 and 3^b against the action of a spring 39 which tends normally to hold it in the position shown in the latter figures, the suspension arms of the bar when in such position contacting with a lug 40 on the supporting bracket as there shown. On the rise of the punching head 21 the tails of the triggers 36 strike the under side of the bar 37 and are tripped thereby, as shown in Fig. 3^b so as to release the bolts 34 and permit them to be retracted by reason of the action of the springs 35 on the heads of said bolts.

In Fig. 6 I have indicated by the letters S' , S^2 , S^3 and S^4 the four cards corresponding to the four sets s' , s^2 , s^3 and s^4 of punch jacks and by the letters n' , n^2 , n^3 and n^4 the four groups of spaces in the transverse row of each card corresponding with the four groups of punch jacks in the corresponding set s' , s^2 , s^3 or s^4 .

Mounted so as to swing upon a shaft or spindle 41 carried by one of the bearings 30 are a series of bell crank levers 42, hereinafter referred to as "key levers", one arm of each of these levers engaging a slot in the spring-supported stem 43 of a key t and the other arm of each of said levers being slotted for the reception of a pin 45 on a key-jack v , said key-jacks being guided in the front and rear bearings 30 so as to slide

therein. There is one key for each of the colored yarns employed in the color boxes, and, in the drawing, the different keys are numbered from 1 to 16 to correspond with the different yarns which they represent, 70 and the corresponding key-jacks v , shown in Fig. 5, are likewise numbered.

Each of the key jacks differs from each of the others, thus, as shown in Fig. 5, the key jack 1 has, with the exception herein-after noted, a straight upper surface but each of the other key jacks has one or more upwardly projecting lugs 46. The key jack 2 has a single lug adapted to act upon the swinging blade 24^a, the key jack 3 has a single lug adapted to act upon the swinging blade 25^a, the key jack 4 has two lugs one adapted to act upon the blade 24^a and the other upon the blade 25^a, the key jack 5 has a single lug adapted to act upon the blade 26^a, the key jack 6 has lugs adapted to act upon blades 24^a and 26^a, the key jack 7 has lugs adapted to act upon the blades 25^a and 26^a, the key jack 8 has lugs adapted to act upon the bars 24^a, 25^a and 26^a, the key jack 9 has a single lug adapted to act upon the blade 27^a, the key jack 10 has lugs adapted to act upon blades 24^a and 27^a, the key jack 11 has lugs adapted to act upon the blades 25^a and 27^a, the key jack 12 has lugs adapted to act upon the blades 24^a, 25^a and 27^a, the key jack 13 has lugs adapted to act upon the blades 26^a and 27^a, the key jack 14 has lugs adapted to act upon the blades 24^a, 26^a and 27^a, the key jack 15 has lugs adapted to act upon the blades 25^a, 26^a and 27^a, and the key jack 16 has lugs adapted to act upon the blades 24^a, 25^a, 26^a and 27^a. The number of blades which will be caused to swing on each operation of the machine will therefore depend upon which of the keys is depressed. If the key corresponding to the key jack 16 is depressed all four of the blades will be actuated and all four of the punch jacks 31^a, 31^b, 31^c, and 31^d will be projected so as to lock in position all four of the punches corresponding to said group, consequently on the descent of the punching head 21 all of the punches of said group will be depressed and four punchings will be formed in the card as represented in connection with color 16 in Fig. 6. If, on the other hand, the key which operates key jack 1 is depressed none of the blades will be actuated and neither of the group of punch jacks 31^a, 31^b, 31^c and 31^d will be projected, consequently the locking bolts 34 corresponding to said group will remain in their retracted positions and the punches 20 corresponding thereto will, on the descent of the punching head 21 be free to rise and the group of spaces on the card will be left blank, as indicated in connection with color 1 in Fig. 6. Depression of any of the other keys will cause the formation of punch holes in one, two or three 126

of the spaces of a group on the card depending upon the actuation of one, two or three of the swinging blades and the projection of one, two or three of the punch jacks of a group.

Each of the key jacks has on its upper side a projecting lug 47 which upon the projection of the key jack, acts to swing forwardly a blade 48 carried by a rock shaft 49 mounted in bearings on the fixed frame of the machine and having a depending arm 50 which carries at its lower end an adjustable set screw 51 adapted to act upon an arm 52 projecting from a rock shaft 53, likewise mounted in bearings on the fixed frame and having an arm 54 carrying escapement pawls 55 and 55^a which coöperate with a toothed escapement wheel 56 secured to a shaft 57, the latter being connected by suitable interposed gears to a shaft 58, having a spur wheel 59 which engages with a rack 60 on the under side of the carriage 23, as shown in Figs. 2 and 3. The swinging blade 48 is normally held in its retracted position

25 by means of a spring 61 located near one end of the rock shaft 49, movement of the blade in this direction being limited by contact of an adjustable set screw 62 on the arm 50 with a stop on the fixed frame of the machine, as shown in Fig. 3, and movement of the rock shaft 53 and its arm 52 in the direction of the arrow Fig. 3 being caused by a coil spring 63. This construction, being substantially that of the carriage mechanism of 30 an ordinary typewriting machine, forms no part of my invention and any equivalent device may be substituted therefor. On each of the punch jacks is a depending lug 65 which, on the retraction of the blade 48, is 35 struck thereby so as to restore the projected punch jacks to their retracted positions.

Operation of any one of the keys *t*, will cause movement of the escapement to the extent of one tooth of the wheel 56 and the 40 lateral movement of the carriage 23 to the extent of one step. When said carriage is at one extreme of its movement the blades 24^a, 25^a, 26^a and 27^a operate in connection with the punch-jacks of the first group of the 45 first set *s'* but all of the remaining punch-jacks both of this group and of the other three groups will be free from the influence of said swinging blades. After the first advance step of the carriage 23 the punch-jacks of the set *s'* will be freed from the action of the blades and the latter will coöperate with the first group of punch-jacks of set *s²*; on the second advance step of the carriage the punch-jacks of the first group 50 of set *s³* will be acted upon, and upon the third advance step of the carriage the punch-jacks of the first group of set *s⁴* will be acted upon. The next four steps in the movement of the carriage 23 will 55 bring into action the second group of

punch-jacks of sets *s'*, *s²*, *s³* and *s⁴* in succession, the next four steps will bring into action the third group of punch-jacks of each of said sets in succession, and the next four steps will bring into action the fourth group 60 of punch-jacks of each of the successive sets. The punch locking bolts for each group of punches will by this time have been properly set and the punch head 21 can now be caused to descend so as to properly punch the first 65 row on each of the four cards. The carriage 23 is now restored to its original position and the cards are moved ahead to the extent of the distance between the transverse rows thereon and the operation can then be 70 repeated for the formation of the second row on each of the four cards.

Supposing that in reading a line of the design the first sixteen colors will represent the sequence 1, 1, 3, 9, 8, 8, 8, 12, 14, 6, 15, 3, 3, 3, 11, 7, the keys *t* will be depressed in like sequence and the operations will be as follows:

Key depressed.	Punches set.	Result.	90
1.....	Group 1, card 1.	Calls yarn 1, color box 1, first position.	
1.....	Group 1, card 2.	Calls yarn 1, color box 1, second position.	
3.....	Group 1, card 3.	Calls yarn 3, color box 1, third position.	
9.....	Group 1, card 4.	Calls yarn 9, color box 1, fourth position.	
8.....	Group 2, card 1.	Calls yarn 8, color box 2, first position.	
8.....	Group 2, card 2.	Calls yarn 8, color box 2, second position.	
8.....	Group 2, card 3.	Calls yarn 8, color box 2, third position.	
12.....	Group 2, card 4.	Calls yarn 12, color box 2, fourth position.	
14.....	Group 3, card 1.	Calls yarn 14, color box 3, first position.	
6.....	Group 3, card 2.	Calls yarn 6, color box 3, second position.	
15.....	Group 3, card 3.	Calls yarn 15, color box 3, third position.	95
3.....	Group 3, card 4.	Calls yarn 3, color box 3, fourth position.	
3.....	Group 4, card 1.	Calls yarn 3, color box 4, first position.	
3.....	Group 4, card 2.	Calls yarn 3, color box 4, second position.	
11.....	Group 4, card 3.	Calls yarn 11, color box 4, third position.	100
7.....	Group 4, card 4.	Calls yarn 7, color box 4, fourth position.	

The punching of the first row of each of the four cards is then effected and all of the cards are advanced one step so as to bring the second row in position to be punched, the carriage 23 is restored to its original position, and the above operations are repeated in connection with the second group of sixteen colors in the line, and so on, until the full sixty rows of each of the four cards have been properly punched, these four cards then representing a complete line of knots from one edge of the fabric to the other. In the 105 operation of the loom, therefore, card 1 will effect setting of the entire set of 240 color boxes and cause them to deliver the proper yarns for the first position, the second card will set all of the color boxes for delivering 110 the proper yarns for the second position, and the third and fourth cards will properly set the color boxes for delivering the yarns for the third and fourth positions, respectively.

Instead of having four sets of lugs 33, one for each set of punch-jacks, the swinging blades may have but one set of such lugs as shown for instance in Fig. 12, so as to act successively upon successive groups of 120 130

punch-jacks of the same set, instead of upon like groups of successive sets, but in this case the carriage 23 will, between the successive operations of the keys *t*, have to be moved as by the operation of an ordinary space key, so as to carry the set of lugs from one group to the next of the same set, or from the last group of one set to the first group of the next set, and the depression of the keys *t* will be determined not by the colors of the successive knots of the sets in a row across the web but by the color of every fifth knot of the set, thus:—1, 5, 9, 13, 2, 6, 10, 14, 3, 7, 11, 15, 4, 8, 12, 16.

15 Although the punching of the cards for use in a loom of the class to which my invention relates is relatively complicated my improved machine can be operated as easily as a typewriting machine and with no more calculation on the part of the operator who has only to depress the keys in the sequence determined by the sequence of colors in a line of the design.

I have described each color box as operating in connection with a set of warp threads comprising four pairs but it will be evident that the set may comprise a greater or lesser number of pairs than four, in which case the number of cards in the set 25 will be correspondingly changed, and although I have described each color box as containing sixteen differently colored yarns more or less than this number may be employed, depending upon the color requirements of the pattern to be produced. Reduction in the number of colors employed may also permit of simplification of the wedge mechanism and the use of a lesser number of wedges than four, in which case 30 there may be a like reduction in the number of jacquard harness cords and of spaces on the card for each color box of the loom and a similar reduction in the number of punch-jacks of a group and of the swinging blades 35 for actuating said jacks, and on the other hand increase in the number of colored yarns may lead to a corresponding increase in the number of wedges, harness cords, card spaces, punch-jacks and operating 40 blades therefor.

Instead of employing separately mounted keys connected to the key jacks by intervening mechanism the keys may, as shown in Fig. 13, be connected directly to the key 45 jacks, or if an operator is thoroughly familiar with the character of the punchings necessary to produce the different colors the punch jacks or punch locking bolts may be operated directly by hand, in order to insure the desired setting of the punches in each group prior to each punching operation.

I claim:

1. A key-board card punching machine 65 having a series of groups of punches for

each of a series of cards, a plurality of keys, and means whereby successive key operations are caused to effect the setting of the punches of one group of each card in succession, and then the setting of the punches 70 of another group of each card in succession.

2. A key-board card punching machine having a series of groups of punches, a plurality of keys, means whereby successive key operations are caused to effect the setting first of the punches of one group and 75 then of another group of the series, and means for simultaneously operating the punches of all of the groups to effect the punching operation.

3. A key-board card punching machine having guides for a series of cards, a group of punches for each card, a plurality of keys, means whereby successive key operations are caused to effect the setting of a 85 group of punches for each card of the series in succession, and means for operating the punches of all of the groups to effect the simultaneous punching of the series of cards.

4. A key-board card punching machine in which are combined a group of punches, a group of punch jacks, a plurality of jack-operating blades, and a plurality of blade-operating key-jacks distinguished from one 95 another, so as to operate said blades in different combinations.

5. A key-board card punching machine in which are combined a group of punches, a group of punch-jacks, a plurality of 100 punch-jack-operating blades, one for each jack of the group, and a plurality of blade-operating key-jacks, distinguished from one another so as to operate said blades in different combinations.

6. A card punching machine in which are combined a series of groups of punches, a corresponding series of groups of punch-jacks, punch-jack-operating blades, and means for shifting the relation of said jacks 110 and blades whereby the latter may be caused to act first upon one group of jacks and then upon another group of the same.

7. The combination, in a card punching machine, of a punching head, a group of 115 punches carried thereby and movable therein, a locking bolt for each punch of the group, a retaining trigger for each bolt, and means for tripping said triggers after the punching operation has been completed.

8. The combination, in a card punching device, of a punching head, a group of punches carried thereby and movable therein, a locking bolt for each punch of the group, a retaining trigger for each bolt, and a tripping bar which is deflected by the triggers when the latter move in one direction but trips the triggers when they move in the opposite direction.

9. A key-board card punching machine 130

in which are combined a fixed bed, a sliding carriage thereon, blades pivotally mounted on said carriage, punch jacks actuated by said blades, key jacks for actuating the blades, and means for imparting step by step forward movements of adjustment to said carriage and its blades.

10. A key-board card punching machine in which are combined a fixed bed, a sliding carriage thereon, blades pivotally mounted on said carriage, punch jacks actuated by said blades, key jacks for actuating the blades, and means for imparting step by

step forward movements of adjustment to said carriage and its blades, the key jacks 15 being constructed to act upon the blades with like effect in each of the successive positions of adjustment of said blades.

In testimony whereof, I have signed my name to this specification, in the presence of 20 two subscribing witnesses.

CHARLES H. LANDENBERGER.
